UNITED STATES PATENT OFFICE.

EDWARD ALLIN STIGGINS, OF BEVERLY, MASSACHUSETTS, ASSIGNOR TO UNITED SHOE MACHINERY COMPANY, OF PATERSON, NEW JERSEY, AND BOSTON, MASSACHUSETTS, A CORPORATION OF NEW JERSEY.

LASTING-MACHINE.

1,081,872.

Specification of Letters Patent. Patented Dec. 16, 1913.

Application filed October 18, 1902. Serial No. 127,116.

To all whom it may concern:

Be it known that I, EDWARD A. STIGGINS, a citizen of the United States, residing at Beverly, in the county of Essex and State of Massachusetts, have invented an Improvement in Lasting-Machines, of which the following description, in connection with the accompanying drawings, is a specification, like reference characters on the drawings 10 indicating like parts in the several figures.

This invention relates to lasting machines. It is herein illustrated as embodied in a machine of the type known as the hand method lasting machine, such as is shown 15 and described in United States Letters Patent No. 584,744, dated June 15th, 1897, and No. 597,321, dated January 11th, 1898, but of course the invention is not limited to use in such a machine as many features of it are 20 applicable to other types of lasting machines.

Certain features of the invention are especially intended to improve hand method lasting machines which are equipped for 25 lasting welt shoes.

Among the features of my invention a very important one consists in providing an improved last-supporting jack by the use of which shoes can be lasted much better 30 than has heretofore been possible, and with less labor on the part of the workman.

It has become customary to use in many grades of shoes straight counters or heel stiffeners, that is, counters which are provided with straight flange portions instead 35 of counters which are provided with molded flanges, and to last the shoe by bending or breaking down the flange portion upon the inner-sole in the same operation in 40 which the upper material is laid over the inner-sole. The advantage of thus breaking down the flange of each counter during the lasting operation is that the counter is thereby conformed to the particular last on 45 which the shoe is being made, and a better fit of the shoe is obtained. But inasmuch as the counter is of stiff material, it is very difficult and laborious for the workman to hold the work up to the machine with sufficient 50 strength to resist the force of the presser as it strikes the upper material and breaks down the counter flange. To over-

come this difficulty as well as to secure other advantages, some of which will hereinafter be pointed out, the machine has been provided with a last-supporting jack so constructed that it will clamp the counter snugly to the body of the last at the counter end thereof. The machine has also been provided with actuating mechanism for 55 raising the jack to present the shoe in operative position against the sole-bottom rest, and for holding the shoe firmly in such position during each operation of the heel lasting devices, and then yieldingly 60 between successive operations of said devices while the shoe is fed along. By this means the shoe is held up to the machine with very little effort on the part of the workman, and better lasting is effected because 65 the shoe is automatically pressed upwardly by the jack in time relation to the operation of the tack driver and to the advance of the reciprocating wiper and tack guide of the machine by which the upper is forced 70 into lasted position, particularly at the heel of the shoe. This arrangement effects a substantial compression of the stock between the last bottom and the wiper and 75 tack guide when the shoe is uplifted by the 80 jack. This compression compacts the shoe stock against the last bottom, forming a definite angular edge or corner at the edge of the shoe bottom and also prepares the stock for the reception of the fastening tack, 85 which at the heel of the shoe is to be clenched against the metallic heel plate of the last, and it leaves the stock, particularly where it is crimped, smoother than it would otherwise be left for the reception of the 90 sole which is to be laid over the lasted upper.

Another important feature of my invention consists in providing an improved presser for forcing the upper material into the angle of union between the feather edge 95 and lip of the inner-sole of the shoe and for forcing a binder of wire or similar material into binding relation with said upper material to hold the upper in lasted position. The presser is constructed and arranged to 100 force the upper over the edge of the last in a direction more or less oblique to the length of the adjacent portion of the edge of the last and preferably comprising a rotatable

disk provided with a scalloped edge forming peripheral fingers. In connection with the described rotary presser I have provided in this embodiment of the invention mechanism for turning it at each operation of the upper manipulating mechanism.

A feature of this invention consists in the combination of a presser which can turn and is adapted to overlie the margin of the shoe bottom for the purpose described with means for driving the presser.

It has heretofore been proposed to provide a lasting machine with a wiper comprising a circular disk having an unbroken periphery which was free to roll in contact with the upper material being lasted and to force said material into the angle of union between the feather edge and lip of the inner-sole. The present construction is an improvement on such a wiper in certain respects, among which may be mentioned that the peripheral fingers are better adapted for engaging the successively lasted portions of upper material and forcing them into said angle of union, and the provision of actuating mechanism enables the presser to be turned in wiping as distinguished from rolling contact with the work, thereby more effectually to force the upper material and the wire into position.

Another important feature of the invention consists in discontinuing the operation of the grippers by rendering the "updraw," or gripper raising and lowering mechanism, inoperative when said grippers are not required for use. The heel portion of the shoe is generally lasted by the action of a horizontally reciprocating combined presser and tack-carrier, and the grippers are not utilized because they would pull the upper out of place. The operator has therefore been obliged to hold the shoe so that the edge portion of the upper was out of reach of the grippers, or to move the shoe out of the range of action of the grippers at each downward movement of said grippers, and then to return the shoe quickly into position to receive the action of the reciprocating presser. Either of these expedients is impracticable if the shoe is supported in a jack while the heel is being lasted. Moreover the unnecessary operation of the grippers involves needless wear upon the machine. By suspending the movement by which the grippers are lowered into gripping position, it is practicable to hold the shoe continuously in operative position by means of the jack while lasting the heel portion, and the workman is relieved of all the labor of presenting the shoe to the lasting devices, except that required for feeding the shoe to present successive portions thereof to the operation of the machine. In this connection may be pointed out one of the advantages of the use of the jack operating mechanism in com-

bination with this type of lasting machine in which the reciprocating wiper and tack block perform the lasting operation when the grippers are out of use. In the prior practice above mentioned of dodging the grippers while lasting the heel the operator returned the shoe in time for the edge portion of the upper and counter to meet the advancing wiper and this return was made in some instances, e. g. while the operator was fresh in the early part of a day's work, with enough force to increase the lasting action of the wiper and more or less to give a beating action that would draw the stock obliquely inward and, in theory at least, improve the lasting of the heel seat. By the described action of the jack which raises the shoe during and to meet each advance of the wiper all the advantages claimed for the hand practice are obtained with certainty and in greater degree than was heretofore possible.

To facilitate the feeding of the shoe, I have provided the bottom rest against which the inner-sole is held by the jack with a rotatable foot or contact-piece which is capable of rolling over the inner-sole as the shoe is fed along.

Another feature of my invention consists in improved mechanism for actuating the grippers. The grippers are carried by relatively movable shanks and are moved, as set forth in detail in said Letters Patent above mentioned, to stretch the upper material over the last and lay it down upon the inner-sole in position to be fastened thereto. The grippers are also given movements from one side of their central position to the other side thereof, and turned on the axis of their shanks when lasting the toe, and sometimes other parts of the shoe, to fold the upper material on itself or plait it, as described in said Letters Patent. Under certain working conditions it is desirable that the turning movements of the grippers should be yieldingly effected to avoid injury to the upper-leather. It has been proposed to effect yieldingly the turning movement in one direction, but in lasting McKay shoes it is customary to use the machine for plaiting first in one direction and then in the other. I have, therefore, provided for yieldingly turning the grippers in both directions and in the illustrated embodiment of this feature of the invention I have modified and improved the earlier mechanism so as to adapt it for performing the double function of yieldingly effecting the turning movement of the grippers in both directions.

These features of my invention and others, including certain combinations of mechanisms and details of construction, will be set forth in detail in the following specification and pointed out in the claims.

In the accompanying drawings, which

show the preferred embodiment of my invention, I have illustrated a lasting machine of the type described in said Letters Patent No. 584,744 and No. 597,321, and have sufficiently disclosed its general features to enable the machine as a whole to be understood and to make clear the connection of the present improvements with the older parts of the machine. I have also illustrated in detail the new mechanism which I have invented. For a more complete description of this type of machine reference is to be had to said U. S. Letters Patent.

Figure 1 shows a side elevation of the upper portion of a lasting machine embodying my invention. Fig. 2 is a side elevation of the lower portion of the machine, illustrating especially the last-supporting jack and its relation to certain coöperating parts of the machine. Fig. 3 is a view partly in section of the jack and its operating mechanism. Fig. 3^a is an enlarged detail of the connection between the jack and its post. Fig. 4 is a sectional view on line 4—4 of Fig. 3. Fig. 5 is a detail view showing the jack sustaining spring, and in two positions an equalizing connection between the jack and said spring. Fig. 6 is a sectional view on line 6—6 of Fig. 2. Fig. 7 is a sectional view of the jack-controlling clutch on line 7—7 of Fig. 6, showing the clutch members in operative engagement. Fig. 7^a is a view similar to Fig. 7, showing the clutch members in inoperative position. Fig. 8 is a plan view of the clutch controller in position to render the clutch inoperative, as seen from the broken line 8—8 of Fig. 7^a. The alternative position of the controller is shown in dotted lines in Fig. 6. Fig. 9 is a side view, on an enlarged scale, of the lower left hand portion of the machine head shown below the dotted line 13—13 of Fig. 1, together with a section of a shoe being lasted. Fig. 10 is a top plan view of the mechanism shown in Fig. 9, and disclosing the rotary wiper and the means for actuating it. Fig. 10^a is a detail on the section line 14^a—14^a of Fig. 10. Fig. 11 is a detail view showing the rotatable contact piece with which the bottom rest is provided. Fig. 12 is a view similar to Fig. 10, with parts broken away to show the gages and the operating mechanism therefor. Fig. 13 is a front view partly in section of the gage mechanism as seen from line 17—17 of Fig. 12. Fig. 14 is a side view partly in section of the gage mechanism as seen from the section line 18—18 of Fig. 13. Fig. 14^a is a left hand side elevation of a portion of one of the gages. Fig. 15 is a front elevation of certain connected parts of the machine, including the cam for providing the updraw movement of the grippers and the mechanism for disconnecting said cam from the driving shaft. Fig. 16 is a side elevation of the disconnecting mechanism. Fig. 17 is a

sectional view on line 21—21 of Fig. 15. Fig. 18 is a top plan view of a portion of the cam disconnecting mechanism and of certain other parts which are operated simultaneously therewith. Fig. 19 is a view of the same parts in a different position. Fig. 20 is a front view of the gripper mechanism, parts being broken away to show the arrangement of the spring for yieldingly enforcing the turning movements of the grippers in both directions. Fig. 21 is a detail of said mechanism with the parts in a different position. Fig. 22 is a sectional view on line 26—26 of Fig. 20.

The frame of the machine comprises a column A having mounted thereon a head B and a plate B' intermediate the column and head and herein referred to as the intermediate plate, said head and plate supporting many of the operating parts of the machine. On the head B is a rest for giving support to the bottom of the last, and a gage 10 has its end face in position to support the edge or side of the last. The shoe having been prepared for lasting by assembling the inner-sole, upper, lining and counter on the last, and pulling over the upper at the toe and sides, as usual, and securing it to the inner-sole by a tack or tacks at each of these places, is supported bottom upwardly against the rest 12 and laterally against the gage 10 in position to be operated upon.

D indicates the main shaft and O indicates a driving pulley thereon. The shaft supports the cams for operating the several mechanisms, including the grippers. Said grippers comprise jaws 14, 16, carried by shanks 13, 15, which are so connected as to permit independent longitudinal movement for opening and closing the grippers, but which move together for imparting other movements to the grippers, as will be explained. The grippers are mounted in the front end of a lever 18 which is pivoted at 19 and connected at its rear end through a spring 25 to an extension 32 of a plate E, see Figs. 1 and 15. The plate E carries a cam roll E' which is received in a groove of a cam 280, by means of which the lever 18 is rocked to raise and lower the grippers, giving them what is known in the art as their updraw movement to stretch the upper.

28 indicates one arm of a rockshaft 26, the other arm 36 of which is acted upon by the cam 40 to turn the shaft. The arm 28 engages with the upper end of the shank 15 of the gripper member 16 to close the grippers when the rockshaft is turned.

50 indicates a rod longitudinally movable in bearings in the head and so connected at 125 its front end to the grippers as to swing them horizontally toward and from the machine for pulling the upper over the inner-sole. The rod 50 is provided with a roll 54^a to be engaged by the surface 54 of the cam 130

40 for moving the rod toward the rear. It is moved in the opposite direction by the spring-actuated lever 50^a, the tension of the spring 53 of which may be adjusted by the device 53^a.

5 The grippers are moved laterally, from side to side of their central position, by a rockshaft 56 having on its rear end a pinion 59 engaged by a segmental rack on a lever 10 60 which is actuated to rock the shaft 56 by a connection (not shown) with the cam 40. The front end of the shaft 56 is provided with a segmental block 57.

15 71 indicates a rockshaft provided at its lower end with a knee-lever 68 and at its upper end with a fork 73 embracing a collar 74 slidable longitudinally of the shaft 56. The shaft 56 is tubular and a shaft 76 is contained therein. The collar 74 is provided with a suitable pin and spiral slot 20 connection with the shaft 76 by which the said shaft is turned in one direction or the other by the adjustment of the collar to the right or the left by the rockshaft 71. The shaft 76 is provided at its front end, see 25 Fig. 20, with a pinion 77 which is in engagement with a sliding plate 63 mounted in the block 57 on the end of the shaft 56 and movable by the pinion 77 across the 30 axis of oscillation of the shaft 56. The plate 63 has an arm 65 to which is pivotally connected at 64 a link α^s joined to a rod 55 having yielding connection with the grippers for moving them laterally from one 35 side of their central position to the other side thereof. The plate 63 is adjusted by means of the shaft 76 and rockshaft 71 to bring the pivotal connection 64 of said plate with the rod 55 either concentric with or eccentric to the axis of oscillation of the shaft 40 56. When said plate 63 is so adjusted that the connection 64 is concentric with the axis of the shaft 56, no lateral movement is imparted to the grippers, but when said connection is eccentric to the axis of the shaft 45 56, the grippers are moved laterally once in each direction during each complete operation of the machine by the oscillation of the shaft 56 by the lever 60, such movement 50 being yieldingly effected through the yielding connection of the rod 55 with said grippers.

55 20 indicates a combined presser and tack-carrier mounted on the longitudinally movable bar 84, see Figs. 1 and 9. The bar is reciprocated by a lever 87, actuated by a cam 88. Tacks are delivered to the tack-carrier 20 from a double raceway 250 by a separating and feeding device 245. The 60 raceway is provided with two channels for supplying different kinds of fastenings, herein represented as different sizes of tacks, it being found advantageous to use longer tacks when lasting the shank and sides than 65 are required when lasting the heel. The

raceway is therefore adapted to be moved to supply the tacks contained in either of its channels to the separating and feeding device 245.

241 indicates a cam disk operated by a finger-piece B^{xx} and connected by plate 240 and link 240^a to the raceway 250, for shifting the raceway to bring the desired size of tacks into position to be fed, see Fig. 18.

90 indicates the driver which is moved in one direction by a suitable cam (not shown) on the main shaft D and is moved in the other direction to drive the tacks by a torsion spring 93 having one end fast to the sleeve bracket 8 and the other end provided 75 with an arm 7 resting on the upper end of the driver.

95 Reference is to be had to said Letters Patent for a detailed description and illustration of the mechanism hereinabove 80 briefly described.

100 Referring now to Figs. 2, 3, 4 and 5, 300 indicates a last-supporting jack mounted on a post 302. The post is connected to a lever 304 by a universal joint comprising the connecting device 310 and the pivot pins 306 and 308. The lever 304 is pivoted at 312 to the column A, and its rear end is cupped out to receive a strut 314. The strut extends obliquely in the plane in which the lever is movable, and its upper end bears against a block 316 which rests against a spring 318 in a socket formed in a lug α on the column A. The spring is strong enough to balance the weight of the post and jack with a shoe in the jack, and to hold the jack yieldingly up with the shoe against the bottom rest at the right elevation for presenting the shoe to the lasting devices. The lower end of the block 316 is cupped out similarly to the end of the lever 304, and both ends of the strut are rounded so that as the lever 304 is moved from the dotted line position in which it is shown in Fig. 5 to the full line position in 110 said figure the strut will make an angle of decreasing efficiency with the direction in which the force of the spring is exerted, and a correspondingly changing angle with the lever, so that a smaller part of the force exerted by the spring is effective for turning the lever. The strut arranged as described, constitutes connecting means for causing the force of the spring to be applied with greatest effect to the lever when the jack is raised to its highest position and with decreasing effect as the jack is lowered into inoperative position and as the strut becomes more and more oblique. The force of the spring may be varied by the adjusting screw 320. The 115 jack has a hollow hemispherical boss 322 adapted to fit into the concave head 324 of the jack-post 302 and permit the jack to have universal movement on the post. 120 326 indicates a clamping plate located in- 130

side the boss and having a curved face concentric with the face of the boss. Through the clamping plate passes a bolt or depending stem 328, which extends 5 through a large aperture in the central part of the boss and through the head of the jack-post. The lower end of the stem is secured to a lever 330 which is fulcrumed at 332 to the post and the other end of which 10 is connected by a link 334 with a lever 336 fulcrumed at 338 to the connecting device 310 which unites the post to the lever 304. The upper end of the stem 328 is surrounded by a collar 339 and by a spring 337 bearing 15 on a flange of the collar and on the plate 326. The spring 337 exerts force enough on the lever 336 to clamp the boss of the jack frictionally between the plate or washer 326 and the head 324 of the jack-post and hold 20 the jack against loose movement on the post. A link 340 is connected by ball and socket joints to the lever 336 and to a rack-bar 342. The rack-bar is movable in a guideway formed between the column A and a bracket 25 E^x which is attached to the column and surrounds the jack-post, as shown, to confine and support it. The rack-bar 342 is engaged by a pinion 344 on a short shaft 346, which is journaled in a sleeve 348. The 30 sleeve is confined in the column A by a screw 349,—see Fig. 6,—but is capable of a slight rotary movement. The shaft 346 has fast on its end opposite the pinion a collar 350 of hardened steel which in turn is surrounded by a hub 352 also of hardened steel. The collar 350 and hub 352 constitute two 35 members of a "Horton clutch". The hub has a lug 352^a and also an arm 352^b. The lug rests upon a spring-pressed plunger 354 40 which is mounted in an arm 355 of the sleeve 348. The sleeve is turned to press the plunger against the lug of the hub 352 and thereby to raise the arm 352^b—as shown in Fig. 7—by a cam 360 on the knee-lever 68 which 45 engages a lug 358 on the sleeve 348, as shown in Figs. 6 and 7. The hub 352 which constitutes one of the clutch members is provided with tapering slots or recesses 366 which receive hardened rollers 368. The 50 rollers are pressed normally toward the smaller ends of the tapering slots by spring plungers 370, and when in said smaller ends of the slots, the rollers are wedged between the outer wall of the slots and the collar 350, which constitutes the other clutch member, whereby the two clutch members are 55 operatively connected. The sleeve 348 is provided with pins 372 which extend into the smaller ends of the slots 366. When 60 the clutch is to be operative the sleeve is turned and held by the cam 360 on the knee-lever in such a position that the pins are out of contact with the clutch rollers 368, as shown in Fig. 7. But when the cam 360 65 is moved from the position shown in Figs. 6 and 7 to the position shown in Fig. 7^a and 8, the sleeve 348 is free to rotate a short distance in the direction of the arrow thereon in Fig. 7, and the weight of the arm 355 of the sleeve and the weight of the arm 352^b 70 of the clutch member 352, together with the parts supported by said arm, turn the sleeve in the direction of said arrow. When the sleeve 348 is thus rotated, the pins are forced against the clutch rollers and move said rollers into the wider parts of the slots 366 where they are out of wedging contact with the two clutch members, and said members are therefore disconnected. The arm 352^b is connected by a link 362 to a lever 363, 75 which is pivoted at 364 to the head B and has a cam surface 365. When the machine is adjusted as shown in Figs. 2 and 7, the cam surface 365 stands in position to be engaged by a cam roll 87^x on the lever 87, 80 heretofore referred to, by which the lever 363 is pressed down and the hub 352 turned slightly at each forward movement of the roll 87^x to clamp the jack on its post and then raise the jack positively. The hub is 85 turned in the opposite direction by the spring plunger 354 when the roll 87^x is retracted, to raise the lever 363 and to un-clamp and release the jack, leaving it sustained only by the spring 318. The arm 90 352^b, when it is depressed while the clutch members are operatively connected, rotates the shaft 346 and raises the rack-bar which, through the lever 336 and the link 334 and lever 330, causes the washer 326 to clamp the 95 boss of the jack securely to the head of the jack-post and hold the jack rigidly to the post. The movement which is imparted to the rack-bar is more than enough to clamp the jack to the post, and when this clamping 100 has taken place and the link 334 can be pulled down no more, the lever 304 is pulled upward by the rack-bar and the jack is lifted to press the shoe against the bottom rest 12 and also against the reciprocating 105 member 20, which constitutes the tack guide and the reciprocating wiper of the machine and which serves the very important function of forming or wiping the upper into position to be tacked in the process of lasting, particularly at the heel of the shoe, and then flattening the shoe stock, which is apt to be more or less crimped at the curved portions of the heel, down upon the up-raised last bottom. The upward position 110 of the shoe is limited by the shoe bottom rest 12 when the member 20 is retracted and the shoe is fed with relation to this rest between the intermittent stock compressing pressures from the jack. This positive raising of the jack is in addition to the normal upward pressure caused by the spring 318. The machine is so timed that the jack is clamped rigidly and then raised at the time 115 when the lasting devices are to operate, and 120 125 130

the parts are maintained in this position by the movement of the roll 87^x over the cam portion of the lever 363 until the tack-driver 90 has been actuated and the lasted portion 5 of upper secured in place. When the cam roll 87^x moves to the right, in Figs. 2 and 3, off from the cam 365, the hub 352 is turned in the direction of the arrow in Fig. 7^a by the spring plunger 354, and the positive upward pull on the lever 304 to press the shoe against the bottom rest is relieved, the pull on the link 334 is slackened and the jack is then free to be turned on the jack-post for feeding the shoe to bring another portion 10 of upper into position to be acted upon by the lasting devices. When the knee-lever is moved to permit the sleeve 348 to turn as described, for disconnecting the clutch, the arm 352^b of the hub 352 is supported in a lower position than when the clutch members were connected, and it therefore withdraws the lever 363 from the path of the roll 87^x, so that said lever 363 is not actuated by the roll, but is allowed to remain 15 at rest. When said knee-lever is adjusted to render the clutch again operative the pins 372 are moved away from the rollers which are then acted upon by plungers 370 to move them into the narrow parts of the slots 366, and simultaneously with the movement of the pins 372, to permit the clutch member to be connected, the arm 355 is elevated to raise the lever 363 into the path of the cam roll 87^x so that the jack will be actuated. 20

35 The jack comprises a base plate 400 in which are guided sliding carriages 402 and 404 adjustable toward and from each other to lengthen and shorten the jack for different sizes of shoes. The adjustment is effected 25 as herein shown by a right and left threaded screw 406, held against longitudinal movement in the bearing 408 in the base plate and provided with an operating crank 410. A casting 412, U-shaped in plan view, has its 30 ends pivoted to the heel carriage at 414, and is adjustably supported at its rear by a screw 416 which bears on the carriage as shown. A last-pin support 420 is pivoted to the carriage 404 at 422 and is provided with 35 a spring-pressed plunger 424 which tips the support forwardly to incline the last-pin toward the toe-supporting mechanism. 412^a indicates upright ears of the U-shaped casting 412, and to these ears are securely fastened springs 436. A heel-band 440 is secured 40 at its ends to the springs 436, and its middle rear portion is supported by a resilient strap 438. The shape of the springs 436 is such that when the last is pressed back against the heel-band the ends of the springs tend 45 to turn inwardly and to press against the shoe at about the ends of the counter. The carriage 402 at the front of the jack supports a vertically movable toe-post 450 which is 50 provided with rack teeth to coöperate with

a pinion 452 carried by a shaft 454 mounted in a bearing in the carriage 402. An operating handle is fast to the shaft 454 and is provided with a pawl for engaging a ratchet which is fast on the shaft bearing to secure the handle down and hold the post in elevated position. A casting 464 is pivoted to the upper end of the post 450 and a toe-rest 466 is mounted on one arm of the casting for supporting the toe portion of the last. 55 A resilient toe-band support 470 is secured rigidly to the casting 464 and carries the toe-band 473. The shape of the toe-band support is such that when the toe-band is pressed against the toe of the last the front arm of the support yields and the side arms are drawn inwardly to force the end portions of the toe-band into clamping contact with the sides of the toe portion of the shoe, so that the whole of the toe portion of the 60 shoe is firmly embraced by the toe-band. The last-supporting jack is not more fully described herein and is not claimed in this application inasmuch as it forms the subject-matter of a divisional application Se. No. 90 65 232,953, filed November 16, 1904.

The rotary presser 140 for forcing the upper material obliquely with relation to the edge of the last over into the angle of union between the feather edge and lip of the inner-sole and for forcing the securing wire into binding relation with the said upper is located in a plane below the intermediate plate B' and below the reciprocating presser and tack-carrier 20,—see Figs. 100 1, 3, 9 and 10. The presser has a hub 142 by which it is rotatably mounted in a plate 143 which is in turn secured by rivets 144 to the underside of the pivotally mounted presser carrier 145. The carrier is cut away 105 at 145^a to overlap and partially cover the presser, as shown in Figs. 9, 10 and 10^a. The carrier is pivoted on a boss B'^a on the intermediate plate B', as shown in Fig. 10^a, being held on said boss by a cap plate b' and a 110 screw b².

147 indicates an arm of the carrier 145, which is provided with gear teeth intermeshing with similar teeth on an arm 148 of the rockshaft 71 heretofore described. 115 This connection between the presser carrier and the rockshaft permits the carrier to be adjusted to present the presser in its operative position as shown in Figs. 9 and 10 for lasting the toe, or in an inoperative position 120 as shown in Fig. 3 when the heel and sides of the shoe are being lasted, and it is not desired to use the rotary presser. Coöperating stops B^a and 147^a limit the outward movement of the presser carrier, and a 125 spring pin 149 mounted in the rocker arm 148 engages shallow recesses 150 in the underside of the intermediate plate B' to retain the presser in adjusted positions.

The periphery of the presser is scalloped 130

to form fingers 141 for pressing the upper into place and between which the tacks may be driven, if tacks are employed, to secure in place the portions of upper lasted with the aid of the rotary presser. The presser bends the upper into the angle of the inner-sole and it will be noted from Figs. 9 and 14 that the presser is arranged and has an edge formation to adapt it to overlie and crowd the wire down into the angle of the upper so that the wire is held from rising while it is being tightened into binding relation to the upper. The wire is drawn progressively under tension from a wire supply, not herein shown, as the shoe is advanced. The machine has provision for effecting this advance or feed movement of the shoe relatively to the wire supply and thereby effecting drawing of the wire into binding relation to the overworked upper. This provision is found in the rotary presser, which is turned in the direction of the feed movement in wiping contact with the upper and the wire a distance equal to the distance between one finger and the next at each step and forces the shoe ahead with it.

For driving the presser a device 153 in the nature of a pawl is mounted on a lateral extension 152 of the horizontally reciprocating bar 84 that moves the tack-carrier 20. The pawl 153 engages the fingers 141 as the bar 84 comes forward and rotates the presser the distance between two fingers. A spring-actuated plunger 154 holds the pawl against the periphery of the presser, and reverse rotation of the presser is prevented by a locking pawl 155 acted upon by a spring-pressed plunger 156. When the presser is in retracted position it is out of operative relation with its actuator.

158 indicates a guide for the wire *w*. The guide is attached to the plate 143 and is moved to and from operative position simultaneously with the presser 140.

The machine is equipped with three gages, namely, a heel-gage 10 having a broad firm abutment against which the heel-band may be pressed when the heel is being lasted; a shank-gage 10^a having a long slender end portion by which the shank may be guided; and a combined fore-part and heel-gage 10^b for use at certain times to guide the shoe when lasting without the jack. When the jack is employed it is not necessary to use a gage for lasting the toe portion of the shoe because the presser 140 acts as a guide for the shoe. The combined fore-part and heel-gage is provided with a sliding block 480 to which is attached a contact-piece 482 by a pivot pin 484 which extends at right angles to the plane of sliding movement of the block, whereby the contact-piece may adapt itself readily to the position and the shape of the portion of the shoe being guided against it.

A spring 486 holds the block normally in the position shown in Fig. 14, but permits it to be moved into the position shown in full lines in Fig. 14^a. This combined fore-part and heel-part gage is described and claimed in United States Letters Patent No. 718,586, granted to me January 13, 1903. It sometimes happens that uppers are cut so small that they will not lap over upon the heel of the inner-sole far enough to allow of the lasting tacks being driven the usual distance inside the edge of the heel. It is, therefore, necessary to guide the heel portions of such shoes with the edges nearer to the driver than is usual. For the purpose of enabling this to be done, the heel-gage 10 may be made in two parts and adjustably connected by a clamping screw 10^x, as shown in Fig. 9, so that the gage can be shortened or lengthened to guide the shoe for positioning the tacks any desired or necessary distance from the edge of the last. The gages are each connected to a gage-carrier 488 by a pivot pin 490, and each gage shank is provided in the rear of the pivot pin with a lug 492 and a shoulder 494. The lugs 492 contact with the face of the carrier 488 when the gages are in their operative position, and the shoulders 494 are engaged by spring-pressed plungers 496 by means of which the gages are held in their operative positions, but which permit them to be turned downwardly into inoperative positions. Each gage is movable independently of the others, so that the desired one may be employed at any time.

When a shoe is to be lasted without the jack, the gage 10^b is employed to guide the fore-part and also the heel, and as the tacks should be driven farther from the edge of the shoe at the heel than at the fore-part and shank, in order to locate them in a different line from that in which the heel nails are subsequently to be driven, the gage 10^b must be adjustable backwardly and forwardly to guide the shoe properly for receiving the tacks at the fore-part and at the heel. For this purpose the gage-carrier 488 is provided with an undercut groove on its upper face which receives a rib 498 on a guide plate secured to the head B. The carrier is provided with a stud 500 which is engaged by a forked arm 502 of a rockshaft 504, journaled in the intermediate plate B'. The rockshaft has on its upper end a lug or finger 506 which is engaged by a forked arm 240^x on the hub of the movable plate 240 which is pivoted to the plate B' at 507. The plate 240 is adapted to be adjusted for turning the rockshaft 504 by a cam disk 241, see Fig. 12, secured to the rockshaft B^x, and provided with an operating arm B^{xx} and an eccentric slot 512 which receives a stud 514 on the plate 240. The plate may be adjusted, by turning the rockshaft B^x, for ad-

vancing or retracting the gage-carrier to position the gage 10^b for guiding the fore-part or the heel of the shoe being lasted.

The cam 280 for giving the updraw movements to the grippers is loose on the shaft D, but is rotated therewith by means of a detachable connection with a collar 101 which is pinned to the shaft D, see Figs. 15 and 17. The collar 101 is provided with a bolt hole 10 to receive a sliding bolt or clutch pin 102 carried by the cam. The bolt is pressed by a spring 103 in the direction to engage the collar 101 and has an operating pin 104 extending through a slot 105 in the periphery of 15 the cam and adapted to be engaged by a cam disconnecting device. The disconnecting device is a wedge-shaped block 106 adapted to be placed in the path of the operating pin 104 of the bolt and to disengage the bolt 20 from the collar on the driving shaft. The disconnecting device also has a shoulder 107 which acts as a stop for the operating pin 104 to bring the cam to rest in the same position each time it is disconnected from the 25 shaft.

The disconnecting device 106 is carried by a rockshaft 109, see Figs. 15 and 16, which is supported at one end in a bearing b³ provided in an arm of the machine head B, and 30 at its other end the rockshaft is supported in a bearing 110 formed in an arm b⁴ of the head B, see Figs. 15, 18 and 19, which arm also contains the upper bearing for the rockshaft B^x. The rockshaft 109 is provided 35 with a worm gear 112 which is engaged by a worm formed in a collar 111 secured to the rockshaft B^x, whereby the shaft 109 is turned by the rockshaft B^x to move the disconnecting wedge into and out of the path of 40 the operating pin on the sliding bolt 102. The wedge is moved into position to disconnect the cam 280 and stop the updraw movement of the grippers when the heel is to be lasted and remains in this position until 45 the lasting of the heel is completed. The rockshaft B^x is also provided with an arm b^x which is connected by a link X^b with one of two pivoted plates X^p, X^s, which rest on the driver guide. Said plates X^p, X^s are connected by intermeshing gear teeth, and when 50 closed together they surround the driver 90 and stand in the path of a collar 90^a which is fast on the driver, and so limit the descent of the driver and thereby cause it to drive 55 the tacks only partially into the work, leaving a portion of the shanks of the tacks sticking up, as it is desirable to have them do in the shank and fore-part of the shoe, see Figs. 2 and 3, to facilitate their removal 60 when the shoe is ready to be sewed.

The rockshaft B^x has operative connection with the raceway, with the gage-carrier, with the plates for shortening the stroke of the driver, and with the means for disconnecting the updraw cam from the shaft D.

Said rockshaft may be turned by the handle B^{xx} into either of two positions. In the first position, shown in Figs. 1 and 19, the raceway is shifted to feed short tacks for use at the heel of the shoe, the gages are in their rearmost position, the plates are withdrawn to permit the driver to have its full stroke, and the disconnecting device 106 is in the path of the clutch pin 104 to stop the updraw movement of the grippers. This is the 70 adjustment for lasting the heel of a shoe. In the second position of the rockshaft B^x, shown in Figs. 12, 15 and 18, the disconnecting device is out of the path of the clutch pin 104, the gages are in their forward position, the raceway is positioned to supply long tacks, and the plates X^p, X^s in the path of the driver, so that the tacks are driven only partially into the work. This is the 75 adjustment for lasting the shank and the 80 fore-part of the shoe.

It will be understood that while the rockshaft B^x, which is connected to the gripper actuating mechanism for rendering it operative or inoperative and to the edge gage 90 for shifting it forwardly and backwardly, is herein shown as connected to a double raceway for causing long or short tacks to be supplied according to the adjustment of said shaft, the invention is not limited to a construction in which different kinds of fastenings are supplied from a raceway containing 95 loose tacks or nails.

The turning movement is given yieldingly to the grippers for twisting the upper 100 in plaiting it, through a lever X^e, see Figs. 1 and 20, which is pivoted on a stud X^e vertically adjustable in the machine head. The lower end of the lever X^e is secured to the connecting rod X^s, which is united by 105 means of the adjustable plate 63 to the head 57 of the rockshaft 56, by which the lever may be operated. The upper end of the lever is provided with a lateral boss 120 which is bored to receive a plunger 125, 110 one end of which is secured to a connecting-rod X⁷. The plunger is provided with heads 126, 127, on either end, which are fitted in bearings 128, 121, in the end portions of the boss, the bearing 121 being removable to facilitate the assembling of the 115 parts. The plunger is provided between the heads 126 and 127 with the collars 131, 132, which are freely movable on the shank of the plunger 125, but are held against the 120 heads by a spring 124. The collars are of greater diameter than the bore of the bearings 128, 121, so that they cannot move with the heads through said bearings. Therefore all the movements of the lever 125 X^e, both in the direction of the arrow in Fig. 20 and in the direction of the arrow in Fig. 21, will be yieldingly imparted to the connecting-rod X⁷. The connecting-rod 130 is secured to a slide X^s which is movable

through a guideway in the end of the up-draw lever 18, to which the gripper shanks are connected. The slide has on one side a rack formation which engages a pinion 5 X^4 on the grippers shank 13, for turning the grippers in either direction. By means of these connections the grippers are turned at each oscillation of the lever X^6 , and the turning movement in each direction is 10 yieldingly effected through the spring 124. The rockshaft 56 which actuates the lever X^6 also imparts the lateral or side-to-side movement to the grippers, so that said lateral movement and turning movements of 15 the grippers take place simultaneously. The mechanism for turning the grippers and moving them laterally is rendered operative or inoperative at the will of the workman by adjusting the slide 63 by means 20 of the rockshaft 71 and its knee lever 68, as hereinbefore described. The rockshaft 71 also has operative connection with the jack-raising mechanism, as herein shown, and with the rotary presser. When said 25 rockshaft and its lever 68 occupy the position shown in Figs. 1, 3 and 6, the jack clutch comprising the members 350, 352 and their associated parts will be connected so that the jack will be locked and raised at 30 each operation of the machine, the rotary presser will be in its rearmost, inoperative position, and the mechanism as herein shown for giving the plaiting movements to the grippers will be rendered inoperative 35 because the slide 63 has been adjusted to position the stud 64 concentric with the axis of oscillation of the rockshaft 56. This is the position of the parts when the heel is being lasted, and also when the shank and 40 sides are being lasted, although it is to be understood that the shoe may be held in the hands of the operator while the shank and sides are being lasted and the jack not employed at that time, but moved idly by 45 its actuating mechanism. When the rock-shaft 71 occupies its alternative position, the jack clutch will be disconnected, the clutch members occupying the position shown in Figs. 7^a and 8, and the jack will 50 remain at rest, the rotary wiper will be in its forward, operative position, and the mechanism for giving the plaiting movements to the grippers will be rendered operative by the movement of the slide 63 into 55 the position shown in Fig. 20. This is the position of the parts when the toe is being lasted. With this arrangement the jack is not actuated to lock and lift it while the toe is being lasted, but is held up yieldingly by the spring 318. If desired, however, the 60 jack-raising mechanism may remain permanently clutched to its actuator, in which case the jack would be elevated during the lasting of the toe as well as during the lasting 65 of the other portions of the shoe. It will

be understood that the reciprocating tack block 20 advances into position over the rotary presser 140 while the latter is being actuated. The tack block thus forms means for holding the rotary presser against upward displacement by the pressure of the shoe against it. 70

The bottom rest 12 comprises a shank 12^a having a recessed foot 12^b, in which is journaled a rotatable contact-piece 12^c to be engaged by the inner-sole when the shoe is held up to the machine to be operated upon. The contact-piece may be in the form of a truncated cone and is mounted on a pintle 12^d with the larger end toward 80 the machine. The surface of the contact-piece is serrated and the serrations preferably point toward the machine so as to hold the shoe against the thrust of the lasting devices, particularly of the reciprocating 85 presser and tack-carrier 20, as it comes forward to break down the counter flange at the heel. The rotatable contact-piece permits the shoe to be fed with greater ease than would be possible if the bottom rest 90 were provided with a non-movable contact-piece, particularly when the shoe is automatically held against the bottom rest by the jack during the feeding movement, as it is when lasting the heel and the toe. The 95 tapering shape of the contact-piece causes the shoe to be turned as it is fed in contact with the rest.

It is sometimes desirable to vary the tension of the updraw spring 25 to cause it to 100 stretch the upper with greater or less force than that provided for by its normal adjustment, and therefore a wedge 22 is interposed between a fixed collar 23 on the rod 32 and a movable collar 23^a against which 105 the spring acts. The wedge is secured to a sliding rod 24 which has an operating handle 28^a by which the operator may at will adjust the wedge between said two collars on the rod 32 to increase or decrease the 110 tension of the updraw spring. It may be desirable when lasting the toe portion of a shoe held in the jack to decrease the tension of the updraw spring, because the toe of the upper has already been wiped over the toe 115 of the last and then clamped against the last by the toe-band, so that it cannot be stretched any further, and therefore it is desirable that only sufficient pull shall be 120 exerted on the marginal portion of this part of the upper to plait it and lay it down upon the inner-sole.

In lasting shoes with this machine it is usual to last the shank and sides first, while the shoe is held in the hands of the operator, 125 then to put the shoe into the jack and last the heel, and finally the toe. The machine is adjusted first with the shank-gage in operative position and the other gages turned down. The rockshaft B^x is turned to move 130

the gage-carrier forward, to cause long tacks to be fed, to put the plates X^p , X^s , in position to shorten the stroke of the driver so that the tacks will be left projecting, and 5 to move the disconnecting device 106 out of operative position so that the grippers may be actuated normally to pull the upper. The rockshaft 71 is positioned so that the rotary presser and the mechanism for giving 10 the plaiting movements to the grippers will remain inactive, and the clutch of the jack actuating mechanism is closed. The shoe, assembled on the last and having been pulled-over, is presented by the operator 15 bottom upward with the inner-sole against the bottom rest 12 and the edge of the shank against the shank-gage. When the machine is started, by a suitable actuating mechanism not herein shown but including a belt 20 for the driving pulley O, the cam 280 acts upon the lever 18 and depresses the grippers while the cam 54, acting on the roll 54^a, draws the grippers toward the head of the machine. The cam 40 then actuates the 25 gripper-closing arm 28 to cause the grippers to grasp the upper. The cam 280 next raises the grippers to stretch the upper, this movement being effected through the spring 25 bearing down upon the lever 18. Thereafter 30 the cam 54 permits the spring 53, acting through the overdraw rod 50, to move the grippers horizontally away from the edge of the last while the cam 280 again lowers the grippers, said two horizontal and downward movements of the grippers combining 35 to cause them to lay the stretched portion of upper down upon the inner-sole while keeping it pulled taut. The cam 88 next causes the sliding presser and tack-carrier 40 20 to be moved forward to wipe and press the stretched portion of upper firmly upon the edge portion or feather of the inner-sole. When the presser has come into holding engagement with the stretched portion of upper, the cam 40 permits the grippers to be 45 opened and the cam 280 begins to raise them. After the grippers release the upper the presser and tack-carrier continue to advance until the driver passage of the tack-carrier is beneath the driver 90, whereupon 50 the driver is forced down by its torsion spring 93 and drives the securing tack which previously had been supplied to the tack-carrier from the raceway by the tack-feeder 245. The driver is then raised by its cam and the tack-carrier and presser are moved by the cam 88 back into their retracted position out of the paths followed by the grippers in their next descent. The 55 workman next feeds the shoe forward into position for the grippers to grasp another portion of upper and thus the lasting operation is carried out by repeated operations of the machine. The tack is left projecting as shown in Fig. 2, because the plates 60 65

X^p , X^s , prevent the driver descending its full stroke. When the shank and sides have been lasted the shoe is placed in the jack with the toe supported on the toe-rest and the edge of the toe-band, and the heel on the spring-sustained last-pin. The toe-post is then raised by the lever 458 and the toe-band forces the last backwardly firmly into the heel-band, causing the last-pin to tip backwardly, while said toe-band wipes the upper 75 along the last toward and then over the toe end of the last, and finally comes into binding contact with the upper around the toe end of the last. The last then is held firmly between the toe-band and heel-band. 80

For lasting the heel of the shoe, the rock-shaft B^x is turned to put the disconnecting device 106 in position for operating the clutch pin 102 to disconnect the cam 280 from the driving shaft and discontinue the 85 vertical or updraw movements of the grippers, so that said grippers remain up out of the way while the heel is being lasted. This movement of the rockshaft B^x also shifts the raceway for causing it to supply 90 short tacks, shifts the plates X^p , X^s , to permit the driver to drive the tacks fully into the work, and shifts the gage-carrier to present the heel-gage, which will be turned up instead of the shank-gage, in position to 95 guide the shoe so that the tacks will be driven well back from the edge of the last. These adjustments having been made the jack is swung over to position the heel-band against the heel-gage and the inner-sole of 100 the shoe up against the bottom rest 12 where it is held yieldingly by the spring 318 acting on the lever 304. When the machine is started the sliding presser and tack-carrier 20 is moved forwardly by the cam 88, the roll 87^x on the lever 87 engages the cam on the jack-operating lever 363, and said jack first is locked rigidly on its post and then is raised positively and held up 105 while the sliding presser and tack-carrier 20 strikes the upstanding flange of upper and counter and breaks down the counter flange and presses it and the upper firmly into place on the inner-sole. The tack-driver then inserts a tack, driving it firmly 110 into and through the pressed-down upper and the inner-sole where it is clenched against the bottom of the last. The heel-band holds the counter snugly against the counter portion of the last and prevents it 115 from springing away when the flange is broken down. As the sliding tack-carrier and presser is retracted, the roll 87^x passes off the cam portion 365 of the jack-operating lever, and the jack is then unlocked and its positive upward pressure relieved, the spring 318, however, continuing to uphold 120 the shoe yieldingly against the bottom rest. The jack may next be moved to feed the shoe for presenting another portion of up- 125 130

per and counter in position to be lasted. The rotatable contact-piece with which the bottom rest is provided facilitates the feeding of the shoe while it is held up by the 5 jack, and the tapering shape of the contact-piece aids in turning the shoe as it is fed to present its different sides to the machine. The lasting of the heel is carried out by repeated operations of the machine, and when 10 completed the jack is turned around to present the toe of the shoe to the lasting devices. For lasting the toe, the rockshaft B^x is readjusted for moving the disconnecting device 106 out of operative position, thereby 15 to permit the updraw cam 280 to become connected again with the driving shaft. This adjustment also shifts the raceway into position for feeding long tacks, but if it is desired to secure the toe portion of the upper 20 per in lasted position by a binder of wire or similar material, as herein illustrated, the raceway is further shifted by means of a supplementary adjusting device 239 to discontinue the delivery of tacks, and the end 25 of the strand of binding wire is secured by taking a turn around the last tack on one side of the shoe while the wire is held taut by a suitable tension device forming part of a wire-supplying mechanism which is 30 35 not herein shown but is fully explained in my prior Letters Patent of the United States No. 946,620, granted Jan. 18, 1910. The heel-gage is turned down into inoperative position because the rotary presser which 40 45 bears against the lip of the inner-sole acts as the gage while lasting the toe of the shoe if the shoe is held in the jack herein shown. The knee-lever 68 is shifted to throw the jack-lifting mechanism out of operation, 50 55 leaving the jack to be held up by its spring 318 only while the toe is lasted. This movement of lever 68 also throws into operation the mechanism for imparting the plaiting movements to the grippers. The free end 60 65 of the wire having been secured to a tack, the shoe is positioned with the rotary presser against the wire at the angle of union between the feather edge and the lip of the inner-sole, and when the machine is started, 70 75 80 85 90 95 100 105 110 115 120 125 130 the grippers pull and plait the upper and lay it down upon the inner-sole. As the sliding tack-carrier and presser comes forward, the rotary presser is turned the distance between two of its fingers to cause a finger to wipe along the plait just formed, and bring a space between the fingers adjacent the portion of upper next to be plaited, the movement being inwardly and rearwardly or substantially in the direction in which the plait was folded. The rotary presser smooths down the plait and holds it as the grippers release their grasp on the upper, and the finger of said presser forces the upper squarely into the angle of union between the feather edge and lip of the inner-sole and the wire firmly against the upper in said angle of union. The rotary presser and the taut wire hold the portion of upper continuously in lasted position while the sliding tack-carrier and presser is retracted and until another portion of upper is plaited and the presser again rotated. It is to be noted that in the curvilinear movement of the presser 140 about its pivot continuous engagement with the upper is maintained by the finger which is for the moment outermost and which presses the upper and wire into the angle against the shoulder of the innersole and this finger receives a movement in the direction of the plaiting and lengthwise of the edge of the shoe. At the same time another finger is advanced transversely across the edge of the shoe but obliquely thereto by the same curvilinear movement of the wiper about its axis. This latter finger extends in advance of the pulling point at which the grippers operate so that in its movement it gathers the upper inwardly and backwardly toward the grippers and in effect extends the range of action of the lasting instrumentalities so that fewer pulls and plaits are required for lasting a toe. The peripheral speed or rate of advance of the wiper is preferably substantially greater than the rate of feed of the shoe so that the fingers have a distinct rubbing action as distinguished from a rolling contact with the stock and each portion of upper and binding wire is or may be acted upon a plurality of times or by a plurality of fingers. It is characteristic of the preferred arrangement of this wiping or pressing mechanism that each pulled portion of the upper is first rubbed transversely of the shoe edge, thus working it toward lasted position, and is then rubbed lengthwise of the shoe edge for setting or forming the upper in lasted position. The rotation of the presser tends to feed the shoe forward in the direction in which the lasting is taking place and may in some instances be relied upon for advancing the shoe in the direction of the feed, thus relieving the workman. This is facilitated by the rotary contact-piece in the shoe-bottom rest, against which the shoe is yieldingly held by the jack. The tapering or truncated cone shape of the contact-piece tends to turn the shoe as the curved toe portion is fed to the lasting devices. As the lasting proceeds around the toe the wire is drawn firmly against the upper to bind the successively lasted portions into said angle of union. When the opposite side has been reached and the toe-lasting finished, the wire is secured to a lasting tack on said opposite side, and the lasting of the shoe is thus completed. The shoe then is ready to be removed from the jack. Sometimes it is desirable to last one or more shoes without putting them in the

jack, and at such times the combined heel and fore-part gage 10^b is employed, as shown in Figs. 12 and 14. The pivoted contact-piece of the said gage adapts itself to the varying contours of the fore-part, toe and heel of the shoe, and said gage is properly adjusted by the rockshaft B^x to guide the shoe for the insertion of tacks near the edge when said rockshaft is turned to cause 5 long tacks to be supplied for the fore-part, and is adjusted to guide the shoe for the insertion of tacks farther from the edge when the rockshaft is turned to cause the raceways to supply short tacks for the heel. 10

Having thus described the preferred form 15 of my invention and its mode of operation, I claim as new and desire to secure by Letters Patent of the United States.

1. In a machine of the class described, an 20 abutment for the shoe bottom, a wiper to press the stock over the shoe bottom, a jack for holding a shoe, means acting on the jack during repeated operations of the machine for pressing the shoe yieldingly toward the abutment and wiper, and means 25 for clamping the shoe firmly against said bottom abutment and wiper during a portion of each operation of the machine.

2. In a machine of the class described, 30 lasting devices, a shoe-rest, a jack for holding a shoe, means for supporting the jack yieldingly with the shoe against the rest during repeated operations of the lasting devices, and means rendered operative at the 35 will of the workman for lifting the shoe against the rest to clamp the shoe at each operation of the lasting devices.

3. In a machine of the class described, an 40 abutment for the bottom of the shoe, a wiper for pressing the upper over the shoe bottom, a jack for holding a shoe, yielding means for sustaining the jack with the shoe against the abutment, and intermittently 45 acting means for pressing the shoe upwardly against the abutment and wiper and then releasing said shoe to permit it to be fed.

4. In a lasting machine, a shoe-rest, lasting devices, a jack, and means for actuating said lasting devices and simultaneously to 50 effect a clamping of the shoe between the jack and the shoe-rest.

5. In a machine of the class described, a 55 bottom rest having a rotatable contact-piece, a movably supported jack for yieldingly sustaining the shoe against the bottom rest, additional means for engaging the bottom of the shoe and means for moving said engaging means in the direction in which the shoe is to be fed.

6. In a machine of the class described, a 60 bottom rest having a tapering rotatable contact-piece, a movably supported jack for yieldingly sustaining the shoe against the bottom rest, and power driven means for engaging said shoe to feed it relatively to

said tapering contact-piece, whereby the shoe is fed in a curved path.

7. A machine of the class described, comprising a jack for holding a shoe, and a reciprocating presser for forcing the upper 70 material of the shoe into lasted position, in combination with mechanism for actuating said presser and mechanism for lifting the jack when the presser is actuated.

8. In a machine of the class described and 75 in combination with lasting devices, a jack for holding a shoe, a support for said jack, means for operating said lasting devices, and means for simultaneously locking said jack to its support.

9. In a machine of the class described, lasting devices, means for actuating said devices, a jack for holding a shoe, a support on which the jack is freely movable for permitting it to be positioned to present the 85 shoe to the lasting devices, and means for locking said jack to its support during an operation of the lasting devices.

10. A lasting machine, comprising a jack for holding a shoe, a reciprocating presser, 90 means for sustaining the jack in position for the shoe to be operated upon, and means for clamping the shoe in said position while the presser is in engagement with the shoe and for releasing the shoe after such engagement.

11. A lasting machine comprising a shoe-rest, a jack for holding a shoe, means for sustaining the jack with the shoe held yieldingly against the shoe-rest, a reciprocating 100 presser for forcing the upper into lasted position, mechanism for actuating said presser, and mechanism for positively lifting the jack when the presser is actuated to clamp the shoe against the shoe-rest and hold it against displacement by the presser.

12. In a machine of the class described, a shoe-rest, a jack for a shoe, a support for the jack, a reciprocating presser for forcing the upper material of the shoe into lasted 110 position, and means for sustaining the jack yieldingly against the shoe-rest, in combination with means for locking the jack on its support and clamping the jack rigidly against the shoe-rest during the forward movement of the reciprocating presser over the shoe for breaking down the upper material into lasted position.

13. In a machine of the class described, a jack for holding a shoe, a rotary presser, 120 means for rotating the presser to force the upper material of the shoe into lasted position, and yielding means for sustaining the jack and holding the shoe against the presser.

14. In a machine of the class described, a 125 jack for holding a shoe, a shoe-rest provided with a rotatable contact-piece, a presser, means for sustaining the jack with the shoe against the rest and the presser, and means for rotating the presser to force the upper 130

into lasted position and feed the shoe under the shoe-rest.

15. In a machine of the class described, a jack for holding a shoe, lasting devices for 5 forcing the upper material into lasted position, a driver for inserting a tack to secure the upper in lasted position, and means for intermittently lifting the jack and supporting it firmly during the insertion of 10 the tack.

16. In a machine for working an upper over a last, a rotatable presser provided with peripheral fingers for forcing the upper into the angle of union between the feather-edge 15 and lip of the sole of the shoe being lasted.

17. In a lasting machine, upper manipulating mechanism comprising a rotatable presser, and means for intermittently turning 20 said presser about an axis substantially perpendicular to the shoe bottom.

18. In a machine of the class described, the combination with mechanism for working an upper over a last, of a rotatable presser provided with peripheral fingers for 25 forcing the worked-over upper into the angle of union between the feather edge and lip of the sole of the shoe being lasted.

19. In a machine for lasting shoes, a rotatable presser constructed and arranged 30 for forcing the upper into the angle of union between the feather edge and lip of the sole, and mechanism for actuating said presser.

20. In a lasting machine, the combination 35 with lasting devices, of a presser, means for adjusting said presser to and from operative position, and actuating mechanism for rotating said presser when it is in operative position.

40 21. In a lasting machine, a rotatable presser, and an actuator therefor, in combination with means for moving said presser into and out of operative relation with said actuator.

45 22. In a lasting machine, a rotatable presser provided with peripheral fingers for forcing the upper into the angle of union between the feather edge and lip of the sole, in combination with means for engaging 50 said fingers to rotate said presser step-by-step.

23. In a lasting machine, a reciprocating lasting device and a rotatable presser, and 55 connections between said lasting device and said presser for rotating the presser at each reciprocation of the lasting device.

24. In a lasting machine, a rotatable presser, means for rotating said presser in one direction, and means for preventing rotation 60 of said presser in the opposite direction.

25. In a lasting machine, means for plaiting the upper of a shoe, in combination with a movable presser for forcing the plaited upper into lasted position, and means for

moving said presser in the direction in which the plait has been formed.

26. In a lasting machine, means for stretching and plaiting the upper of a shoe, in combination with a rotatable presser and means for rotating the presser in the direction in which the upper is stretched and plaited. 70

27. In a lasting machine, means for stretching and plaiting the upper of a shoe, 75 in combination with a rotatable device having peripheral fingers and notches adjacent said fingers, and means for rotating said device step-by-step to bring the fingers successively over the plait last formed and the 80 notches opposite the portions of upper next to be plaited.

28. A lasting machine, comprising devices for stretching the upper of a shoe, a rotatable presser, and means for rotating it, 85 said presser being adjustable to and from position for operating on the work, in combination with mechanism for rendering said stretching devices operative to plait the upper when the presser is adjusted into operative position. 90

29. A lasting machine, comprising grippers, automatic operating mechanism, including means for moving said grippers toward and from the sole of the shoe being lasted, and means to render said operating mechanism inoperative to lower the grippers toward the sole without affecting the other movements of the grippers. 95

30. A lasting machine, comprising grippers and mechanism for moving said grippers to stretch the upper of a shoe, said mechanism comprising a driving shaft, a cam, and means detachably connecting said cam with said shaft, said parts being arranged to cause the cam to hold the grippers raised above their gripping position when the cam is disconnected from the shaft. 100

31. A lasting machine, comprising grippers and mechanism for moving said grippers to stretch the upper of a shoe being lasted, said mechanism comprising a driving shaft, a cam, and means for detachably connecting said cam to said shaft; and means under the control of the operator for actuating said connecting means to discontinue said movements of the grippers and maintain the grippers in elevated position. 110

32. A lasting machine comprising grippers, operating mechanism for moving the grippers toward and from the inner-sole of a shoe being lasted, and means to discontinue said movement of the grippers and support them away from the shoe. 115

33. In a lasting machine, the combination with grippers for pulling an upper over a last, tack-supplying mechanism adjustable for supplying long or short tacks at the will 125 130

of the operator, mechanism for driving tacks, and means for discontinuing the movement of the grippers in the direction for pulling the upper when the tack-supplying mechanism is adjusted for feeding short tacks.

34. In a machine of the class described, a jack, a rotatable presser, actuating mechanisms for each of said devices and means 10 under the control of the operator for rendering one of the actuating mechanisms operative when the other is inoperative.

35. In a machine of the class described, a jack, actuating mechanism for said jack, and 15 a rotatable presser movable into and out of operative position, combined with controlling means for rendering said jack actuating mechanism operative when the presser is in its inoperative position.

36. In a machine of the class described, a jack, actuating mechanism for said jack, grippers, actuating mechanism to cause the grippers to plait the upper, and controlling means for rendering said jack actuating 25 mechanism inoperative when the said gripper actuating mechanism is operative.

37. In a lasting machine, a shoe-bottom rest provided with a revolute contact-piece journaled thereon for free rotary movement, said contact-piece being in the shape 30 of a truncated cone and arranged with its larger end toward the edge of the shoe to adapt it to assist in turning the shoe while the end portions are being lasted.

38. In a lasting machine, grippers for pulling an upper, a presser, and means to actuate the presser to force the upper inwardly over the shoe bottom and to tend to feed the shoe forwardly, combined with a 40 bottom rest provided with serrations to resist movement of the shoe by the presser in forcing the upper over the last bottom and formed and arranged to tend to cause the shoe to be turned as it is advanced by the 45 presser.

39. In a lasting machine, a presser and means for actuating it to force the upper inwardly from the edge of a last and rearwardly with relation to the direction in 50 which the lasting operation is progressing.

40. A lasting machine having means for positioning a shoe, a reciprocating presser, means for actuating said presser in a direction substantially perpendicular to the edge 55 of the last for forcing the upper inwardly over the last bottom, a second presser, and means for actuating it over the shoe bottom in a direction oblique to the edge of the last.

41. In a machine of the class described, a 60 shoe-rest provided with a tapering roller for engagement with the shoe to be lasted, and a rotatable presser for forcing the upper material into lasted position, said presser and the tapering roll of the shoe-rest coöoperating 65 to feed the shoe in a curved path.

42. In a machine of the class described, a shoe-rest provided with a rotatable contact-piece for engagement with the shoe to be lasted, a presser for forcing the upper material of the shoe into lasted position, and 70 means for actuating said presser in the direction to force the upper material into lasted position and to advance the shoe in the direction of feed.

43. In a machine of the class described, a 75 jack for holding a shoe to be lasted, yielding means for sustaining the jack, a rest against which the bottom of the shoe in the jack is pressed by the sustaining means, a rotatable contact-piece in the rest for engagement by the shoe, means for lifting the jack to clamp the shoe against the rotatable contact-piece, intermittently operating means for acting on the shoe while it is so clamped, and means for discontinuing the 80 clamping movement in time relation with the movement of the intermittently operating means and permitting the jack to be moved to feed the shoe under the rotatable contact-piece of the rest while the jack is 85 sustained yielding against said rest.

44. A machine of the class described having, in combination, a vertically unyielding wiper, means for advancing the wiper over the shoe bottom to bend a portion of upper 90 material over the edge of the shoe and lay it in lasted position, a support for the shoe, and automatic power mechanism operating intermittently through said shoe support in timed relation with the wiper to raise the 100 shoe while the wiper is being advanced whereby the wiper may bend the upper by engagement therewith above the plane of the shoe bottom and be caused to force the upper downwardly and inwardly with increasing friction as it advances.

45. In a lasting machine, grippers, and means for actuating the same to stretch and plait the upper, in combination with yielding means for turning said grippers axially 110 in one direction or in the reverse direction during the plaiting operation, said means comprising a lever having a chamber therein, a plunger movable in bearings in said chamber, said plunger having enlarged portions near its ends, collars loose on said plunger between said enlarged portions and adapted to be stopped thereby and by the said bearings, and a spring interposed between said collars, in combination with a 115 rod connecting said plunger with the grippers, whereby movement of said grippers imparted through the lever will be effected yieldingly in either direction.

46. In a lasting machine, the combination 125 with a rotary presser and a reciprocating presser, of means for actuating said pressers together for forcing the upper material into lasted position.

47. In a lasting machine, the combination 130

with a rotary presser and a reciprocating presser, of a carrier for said reciprocating presser and a pawl supported on said carrier and arranged to coöperate with the 5 rotary presser to turn the latter as the reciprocating presser is actuated.

48. In a lasting machine, the combination with a rotary presser, of a reciprocating presser, and means for advancing the reciprocating presser into a position over the 10 rotary presser and for turning the rotary presser during the advance of the reciprocating presser.

49. In a lasting machine, the combination with a thin rotary presser formed to force 15 the upper into the angle of union between the feather edge and lip of the inner-sole of a shoe pressed upwardly against said presser, of means for actuating said presser, and means arranged to occupy a position for 20 holding the rotary presser against upward displacement during its actuation.

50. In a lasting machine, the combination with a rotary presser and a reciprocating 25 presser, of means for actuating said pressers, and means for rendering one of said pressers inoperative while the other presser continues in operation.

51. In a lasting machine, the combination with grippers, means for actuating the 30 grippers to pull the upper, and means for causing the grippers to plait the upper, of a rotatable presser, means to actuate the presser, and means under the control of the 35 operator for simultaneously rendering operative or inoperative the rotatable presser and the means for causing the grippers to plait the upper.

52. In a machine for working an upper 40 over a last, the combination with upper stretching means, of a circularly movable presser, and means whereby said presser may be actuated in a curved path transversely across the edge of the shoe for forcing the stretched upper over the inner-sole 45 of the shoe.

53. In a machine for working an upper over a last, the combination with upper stretching means, of a rotatable presser, 50 means whereby said presser may be actuated to force the stretched upper into the angle of union between the lip and feather edge of the innersole, and a binder guide arranged with relation to the presser to present a 55 binder extending therefrom to the shoe in the path of said presser whereby the presser may force the binder into position for securing the upper in overworked position.

54. In a lasting machine, the combination with means for gripping and pulling an upper, of a presser arranged to act on different pulled portions of the upper successively, and means for actuating the presser to force the upper inwardly from the edge 60 of the shoe and rearwardly with relation to

the direction in which the operation is progressing.

55. In a lasting machine, the combination with means for gripping and pulling an upper, of a presser, and means for turning the presser to force the upper inwardly from the edge of the shoe and backwardly with relation to the direction in which the operation is progressing. 70

56. In a lasting machine, the combination with means for working an upper over a last progressively by repeated operations of the machine on different portions of the upper, of a rotatable presser for engaging the upper and forcing it into contact with the inner-sole, and means for actuating said presser over the upper inwardly and rearwardly with relation to the direction in which the lasting operation is advancing. 75

57. In a lasting machine, the combination with a thin rotary presser formed to force the upper into the angle of union between the feather-edge and lip of the innersole of a shoe pressed upwardly against said presser, and means for intermittently lifting the 80 shoe against said presser, of means for actuating the presser while the shoe is lifted, and means arranged to occupy a position for holding the rotary presser against upward displacement during its actuation. 85

58. A lasting machine having mechanism for working an upper over a last and securing it in the angle of union between the feather-edge and the lip of the innersole, said mechanism comprising a rotatable member constructed and arranged to position the shoe by engagement with the shoe bottom at said angle of union, and automatic means for turning said rotatable member. 90

59. In a lasting machine, the combination with grippers, of means for actuating the grippers, an edge rest shiftable forwardly and backwardly, and means under control of the operator for rendering the grippers inoperative and simultaneously shifting the 95 edge rest. 100

60. In a lasting machine, the combination with a driving shaft, of grippers movable downwardly into position to grip the upper and upwardly to pull the gripped upper, 115 means intermediate the driving shaft and grippers for actuating the grippers, and means under control of the operator for maintaining the grippers in an elevated position during repeated rotations of the 120 driving shaft.

61. In a lasting machine, the combination with grippers for pulling an upper over a last, of mechanism for supplying different kinds of fastening material for securing the 125 overworked upper, and means under control of the operator for suspending the pulling movements of the grippers when one kind of fastening material is being supplied and effecting such pulling movements when a 130

different kind of fastening material is being supplied.

62. In a lasting machine, the combination with grippers for working an upper over a last, means for inserting fastenings to secure the upper in overworked position, and a shiftable edge gage adapted to position the work in different relations to the fastener inserting mechanism, of means under the control of the operator for rendering the grippers inoperative when the edge gage occupies one position and for rendering the grippers operative when the edge gage occupies a different position.

63. A step-by-step type of lasting machine arranged to permit the shoe to be fed past the point at which the lasting operation is performed and having, in combination, a pivotally mounted presser and means for actuating it in a curved path across the edge of the shoe bottom for working an upper progressively into lasted position by the action of said presser upon adjacent portions of the upper successively, said actuating means comprising a continuously running driver and connections therefrom for effecting intermittent operation of the presser over the shoe bottom.

64. A lasting machine having mechanism for working an upper over a last, comprising a presser supported in a plane substantially parallel with the plane of the last bottom, and means for imparting to said presser an angular advancing movement to do its work.

65. A lasting machine having mechanism for working an upper over a last, comprising a presser, and means for moving the presser about an axis inwardly over the shoe bottom and backwardly with relation to the direction of progress of the lasting operation.

66. A lasting machine having mechanism for working an upper over a last, comprising a presser, and means for actuating it intermittently over the shoe bottom, said machine having provision for imparting to the acting portion of the presser a component of lateral movement during its advance over the shoe bottom.

67. A lasting machine having mechanism for working an upper over a last step by step and forcing it into the angle of union between the feather edge and the upstanding lip of the innersole, comprising one presser having a portion adapted to rest upon an overworked section of upper to hold it in the angle and a portion movable inwardly to crown another section of upper into the angle, combined with means for actuating the presser.

68. In a machine of the class described, the combination with means for forming or wiping the upper of a boot or shoe over the

bottom of a last in the process of lasting, 65 and means for actuating said forming means, of a member adapted to engage the sole of the shoe from above, a member to support said shoe and its last yieldingly from below, and means for actuating said latter member 70 toward the other to clamp the last.

69. In a lasting machine, the combination with means for forming or wiping the upper of a boot or shoe in the process of lasting, and means for actuating said forming 75 means, of a member adapted to engage the shoe from above, a jack to support the shoe and its last from below and means for automatically lifting said jack in timed relation to the movement of the wiping means to 80 clamp the last between it and said member.

70. In a lasting machine, a tack driver, a reciprocating wiper, a lasting jack and operating means therefor operated in timed relation to the tack driver, said lasting jack 85 and its operating means being arranged to press the last and shoe vertically up simultaneously with the operation of the tack driver against the wiper and tack driver in opposition to their downward pressure on 90 the bottom of the last, the aforesaid mechanism including means for compressing vertically the crimped leather down upon the bottom of the last as it is being laid by the wiping movement and pressure of said 95 wiper.

71. In a lasting machine, tack driving mechanism and its operating means, a wiper, operating means therefor operating in timed relation to the tack driving mechanism, to 100 engage the shoe when a tack is driven, a jack for holding the shoe with relation to said tack driving mechanism and wiper, and automatic means for forcing said jack and its shoe strongly against said wiper each 105 time a tack is driven.

72. In a lasting machine, tacking mechanism including a tack guide, lasting mechanism including a lasting jack, means for imparting an up-and-down movement to said 110 jack with relation to said tack guide, and a laterally extending upper compressing surface on the lower end of said tack guide which is maintained vertically stationary in engagement with the shoe bottom during the 115 upward movement of the jack for coöperating with said lasting jack in flattening the leather and which constitutes a rigid abutment.

73. A machine of the class described, having, in combination, an upper rubbing tool having continuous engagement with the shoe, means for supporting and guiding the tool, and means to actuate the tool to rub adjacent portions of a shoe fed under it first 120 transversely of the edge of the shoe and then lengthwise thereof.

74. A machine of the class described hav-

- ing, in combination, means constructed and arranged to force an upper over the feather of an innersole and toward the lip of the innersole, and mechanism to actuate said means in a curved path to cross the shoe edge first transversely of the feather and then to rub substantially lengthwise of the feather in one continuous movement.
75. A machine of the class described, having grippers for pulling an upper over a last and a wiper arranged to engage the upper in advance of the grippers and move backwardly to gather the upper in toward the grippers and press it over the edge of the last.
76. A machine of the class described, having grippers for pulling an upper over a last and a wiper arranged to engage the upper that is being directly pulled and also a portion of the upper located in advance of the grippers, and means for actuating the wiper to press the portion of upper that is in advance of the grippers inwardly and backwardly toward the grippers.
77. A machine of the class described, having grippers, means for actuating the grippers to pull the upper and to plait it, a wiper, and means for actuating it in the direction of the pulling and plaiting movement.
78. A machine of the class described, having grippers, means for actuating the grippers inwardly over a last and laterally to plait the upper and lay it over the last bottom, a wiper and means for actuating it to gather the stock inwardly and backwardly over the last bottom.
79. A machine for lasting a shoe progressively by repeated operations upon successive portions of the upper and having a wiper and means for actuating the wiper to gather portions of the upper and force them inwardly and backwardly to crimp the upper on the shoe bottom.
80. A lasting machine constructed and arranged to work an upper over a last progressively by repeated operations applied to successive portions as the shoe is fed past the machine and having a wiper with an acting face longer than the length of the normal feeding movements of the shoe, and means for actuating the wiper whereby portions of the upper receive a plurality of operations of the wiper.
81. A machine of the class described, having a wiper with an acting edge one end of which is adapted to rest continuously upon the upper, and actuating means for imparting to the wiper a curvilinear movement to press the upper into lasted position.
82. A machine for progressively working an upper over a last and securing it, comprising a device for placing a binding wire in position to hold the upper against the shoulder or lip of the shoe innersole, and means for actuating said device lengthwise of the wire against said shoulder for seating the wire.
83. In a lasting machine, mechanism for working an upper into lasted position having provision for wiping the upper transversely across the edge of the last in one operation in a direction oblique to the length of the shoe edge when the shoe is in its normal position for receiving the operation of the machine and for rubbing the same portion of the upper lengthwise of the edge of the last in a succeeding operation.
84. A machine for working an upper over a last by repeated operations applied to successive portions of the shoe, said machine having a wiper arranged to force a portion of the upper transversely over the last toward lasted position in one operation of the machine and to rub that portion of the upper lengthwise of the edge of the last in a succeeding operation of the machine.
85. In a lasting machine, lasting means having a substantially continuous acting face extending around the toe of a shoe and means for actuating it to wipe the upper up the side faces to the edge of the last bottom and hold the upper clamped to the last and free from wrinkles about the edge of the last bottom, in combination with grippers adapted to operate step by step around the toe of a shoe held by said first mentioned means for working the margin of the upper into lasted position, and means for imparting to the grippers plaiting movements for folding the margin of the upper upon the shoe bottom.
86. In a lasting machine, wiping means, and actuating mechanism for causing said means to wipe one portion of upper transversely of the shoe edge while wiping lengthwise of the shoe edge a portion which was wiped transversely in a previous operation of the machine.
87. A machine of the class described having, in combination, a rotary presser constructed and arranged to engage the upper in the angle between the feather edge and the lip of an innersole on a shoe bottom, and means for relatively actuating said member and the shoe to form the upper into said angle.
88. A machine of the class described having, in combination, a rotary presser constructed and arranged to engage a binding wire superimposed on the upper in the angle between the feather edge and the lip of an innersole on a shoe bottom, and means for actuating the presser over the wire to seat it in binding relation to the upper in said angle.
89. A machine of the class described having, in combination, a rotary presser con-

structed and arranged to engage the upper in the angle between the feather edge and the lip of an innersole on a shoe bottom, and means for actuating the rotary presser 5 at a greater peripheral speed than the feed of the shoe to cause it to form the upper into said angle.

90. A machine of the class described arranged to last a shoe step by step by repeating cycles of the machine as the shoe is advanced to present different portions to be operated upon and having, in combination, a rotary presser constructed and arranged to engage a binding wire upon the upper in 15 the angle between the feather edge and the lip of an innersole on a shoe bottom to force the upper and wire into said angle, and means for actuating the presser at a greater peripheral speed than the shoe is advanced.

91. In a machine of the class described, the combination with means for working an upper over a last, of additional means for guiding a binder into position to hold the upper, said overworking means comprising 20 a wiper adapted to hold the binder down upon the upper while the binder is being drawn into binding position and means whereby the wiper may be actuated during each cycle of the machine to overwork the 25 upper while continuing throughout its operation on the shoe in position to hold the wire down.

92. In a machine of the class described, the combination with means for working an 30 upper over a last, of additional means for guiding a binder into position to hold the upper, and means tending to produce a relative movement between the last and the binder guiding means in a direction substantially lengthwise of the binder and therefore tending to draw the binder about the shoe, said overworking means comprising 35 a wiper adapted to hold the binder down upon the upper while the binder is being drawn into binding position.

93. In a machine of the class described, a 40 rotary presser to engage the shoe bottom and force the upper into overworked position in the angle of union between the feather edge and shoulder of the innersole, and actuating mechanism operatively connected with the presser, said presser being formed and arranged to overlie and crowd down into said angle a binding wire to hold 45 the upper in lasted position.

94. A machine of the class described having, in combination, means for working an upper over a last into position to be bound by a wire anchored at one side of the shoe 50 and extending about the toe to an anchor at the other side, wire guiding means, said machine having provision tending to produce a relative movement between the last and the wire guiding means in a direction substantially lengthwise of the binding wire 55

and therefore tending to draw the binding wire about the shoe, said overworking means including a wiper between which and the shoe the wire is guided into holding position, and actuating mechanism operatively connected with the wiper. 70

95. A machine of the class described having, in combination, means for working an upper over a last into position to be bound by a wire extending about the toe from an anchor on one side to an anchor on the other side, and wire guiding means, said machine having provision tending to produce a relative movement between the last and the guiding means in a direction substantially 75 lengthwise of the binding wire and therefore tending to draw the binding wire about the shoe, and said overworking means comprising a wiper adapted to hold the wire down upon the upper while the binder is 80 being forced into binding position, and means for actuating the wiper to press the upper into lasted position.

96. In a machine of the class described, the combination with means for working an upper over the toe portion of a last into position to be held by a binder of wire or the like anchored at one side of the shoe and extended around the toe to the other side of the shoe, of a binder guide, and means tending to produce a relative movement between the last and the guiding means in a direction substantially lengthwise of the binding wire and therefore tending to draw the binder about the shoe, 95 said machine including means arranged to hold the wire down upon the upper while it is being drawn into position to bind the upper and actuating mechanism therefor. 100

97. In a machine of the class described, the combination with means for working an upper over the toe portion of a last into position to be held by a binder of wire or the like anchored at one side of the shoe and extended around the toe to the other side of the shoe, of a binder guide, and additional means acting in the direction for effecting relative movement of the guide and the shoe to place the binder around the shoe from one anchoring point toward the 110 other anchoring point. 115

98. In a machine of the class described, the combination with means for working an upper over the toe portion of a last into position to be held by a binder of wire or 120 the like anchored at one side of the shoe and extended around the toe to the other side of the shoe, of a binder guide, and automatically operating means acting in the direction for effecting relative movement of 125 the guide and the shoe to draw the binder into holding relation to the upper and maintain it under tension.

99. In a machine of the class described, the combination with means for working an 130

upper over the toe portion of a last into position to be held by a binder of wire or the like anchored at one side of the shoe and extended around the toe to the other side of the shoe, of a binder guide, and additional means acting in the direction for effecting relative movement of the guide and the shoe to carry the binder around the shoe from one anchoring point toward the other anchoring point, said machine being constructed and arranged to maintain the binder under tension in holding relation to the overworked upper.

100. In a machine of the class described, 15 the combination with a wiper to rub an upper inwardly over the edge and bottom of a last, and means for actuating the wiper to do its work, of a yieldingly upheld last support relative to which the last occupies 20 a constant position during the operation of the wiper, and means operatively connected with the wiper actuating means for increasing the pressure of the last toward the wiper when the wiper advances.

25 101. In a machine of the class described, the combination with a wiper to rub an upper inwardly over the edge and bottom of a last and means for actuating the wiper to do its work, of a yieldingly upheld last 30 support, means operatively connected with the wiper actuating means for increasing the pressure of the last toward the wiper when the wiper advances, and means associated with the wiper to insert a tack in 35 the wiped over upper at a time when the shoe stock is under maximum pressure between the wiper and the last.

102. A lasting machine, having, in combination, a last support, a heel band adapted to clamp the upper and the heel stiffener to the side faces of the last and hold it during a lasting operation, a lasting device, means to operate it to bend the marginal portion of the upper materials inwardly 45 over the edge of the last bottom, and means operating in timed relation with the advance of the lasting device to actuate said device and the last support relatively to compress the shoe stock between said device and the last bottom and coöperate with the heel band to shape the stiffener and the upper at and adjacent to the edge of the shoe.

103. A lasting machine, having, in combination, a last support, means adapted to press the upper and the heel stiffener of a shoe against the side face of the last during a lasting operation, a lasting device, and means to actuate it automatically to press 55 the margin of the upper and the stiffener inwardly and downwardly upon the last bottom, and means for automatically raising the last support and side presser relatively to said lasting device to compress and shape 60 the shoe stock.

104. A lasting machine, having, in combination, a last support, means adapted to press the upper and the heel stiffener of a shoe against the side face of the last during a lasting operation, a lasting device, and means to actuate it automatically to press the margin of the upper and the stiffener inwardly and downwardly upon the last bottom, means for automatically raising the last support and side presser relatively to 70 said lasting device to compress and shape the shoe stock, and power driven means to secure the upper and stiffener to the shoe innersole before the shoe is released. 75

105. A machine of the class described having, in combination, a wiping tool having continuous engagement with the shoe, means for supporting and guiding said tool, and actuating mechanism for moving an operative face of said tool always in a curved path over a portion of upper transversely across the feather of the inner sole in one operation of the machine and longitudinally along the feather in a subsequent operation of the machine. 80

106. In a lasting machine, means for holding and automatically clamping a last and upper in position to be lasted, means for lasting the upper, and additional means to assist in placing a wire around the toe in binding relation to the overworked upper. 90

107. In a lasting machine, means for holding and clamping a last and upper in position to be lasted, means for lasting the upper, additional means to assist in placing a wire around the toe in binding relation to the overworked upper, power operated mechanism for the aforesaid parts, and means within control of the operator enabling him to stop the machine with the wire under tension. 100

108. In a lasting machine the combination with upper wiping means and actuating mechanism therefor, of a pivotally mounted member adapted to be turned in the direction to assist in placing a securing wire in upper holding position around the toe of the shoe being lasted, and means for turning said member. 110

109. A lasting machine having in combination, means for working the edge portion of an upper over a sole on a last, operating means therefor, means to support the shoe from below, means to engage the shoe bottom from above, and means operating in timed relation to the movements of the overworking means to raise and lower the shoe support relatively to the overworking means and to said bottom engaging means. 115

110. A lasting machine having in combination, means for working the edge portion of an upper over a sole on a last, operating means therefor, means for supporting and holding the shoe, means to engage the sole, and means for raising and lowering. 120 125 130

the shoe support relative to the overworking means and in time relation to the movement of said means.

111. A machine of the class described having, in combination, a last, means for wiping an upper over the edge of said last, means for applying pressure to said last in the direction to press the upper against the wiper during one period of operation of the machine, and means for applying additional pressure to said last in the same direction during another period of said operation.

112. A lasting machine having, in combination, a presser which can turn and which is adapted to overlie the margin of a welt shoe bottom for pressing the upper into the angle between the feather and the lip of the innersole, and means for driving said presser arranged to impart movement to the presser in a circular path transversely across the edge of the shoe bottom.

113. In a lasting machine, a lasting device and a circularly movable presser, actuating mechanism, and connections from said lasting device and from said presser to the actuating mechanism for imparting circular movement to the presser transversely across the edge of a shoe in time relation with the movement of the lasting device.

114. In a lasting machine, grippers and mechanism for actuating them to stretch and plait the upper of a shoe, in combination with a rotatable presser comprising a disk having a portion projecting peripherally beyond another portion of the disk, and actuating mechanism operating in time relation to the gripper actuating mechanism to bring a high or peripherally projecting portion toward and over the shoe bottom when a plait has been formed and then a low portion of the presser toward the shoe bottom preparatory to stretching and forming another plait in the upper.

45 115. A machine of the class described ar-

ranged to last a shoe step by step by repeated cycles of the machine as the shoe is advanced to present different portions to be operated upon and having, in combination, a wiper, means for advancing the wiper over the shoe bottom to bend a portion of upper material over the edge of the shoe and lay it in lasted position, a support for the shoe, and automatic power mechanism operating intermittently through said shoe support in timed relation with the wiper to raise the shoe while the wiper is being advanced whereby the wiper may bend the upper by engagement therewith above the plane of the shoe bottom and be caused to force the upper downwardly and inwardly with increasing friction as it advances.

116. In a machine of the class described, the combination with a reciprocating tack block having a wiping face on its lower side, of a jack for holding a shoe to receive the action of said wiping face, and means moving with the tack block and having operating connection with the jack to lift the shoe against said wiping face at the end of the advance of the tack block.

117. In a machine of the class described, the combination with a reciprocating block having a wiping face on its lower side, of a jack for holding a shoe to receive the action of said wiping face, a cam, and operating connections therefrom to the jack through which the shoe is given an abrupt lift against said wiping face at the end of its advance and is released immediately after the beginning of the return movement of said block.

In testimony whereof I have signed my name to this specification in the presence of two subscribing witnesses.

EDWARD ALLIN STIGGINS.
